UNITED STATES PATENT OFFICE

PAUL R. STEVENS, OF PORTLAND, MAINE

TOY CHEST

Application filed July 25, 1928. Serial No. 295,251.

In the conception of this invention I have had in mind the fact that in nearly every home the very young members are generally provided with a considerable number of toys of various kinds, but unless they are children of affluent parents seldom have a play room or even facilities where the toys may be collected and stored after the play time is over.

As a consequence, the toys are scattered throughout the different rooms of the house and this causes, oftentimes, more or less annoyance to the older members of the family group.

My present invention, which relates generally to toys, has as its primary object the providing of a convenient receptacle in which a larger portion of the young folks' toys or play-things may be kept or deposited after being used. In an incredibly short time the children will acquire the habit of systematically returning the toys to their proper place, and once this habit is formed will tend to influence them in becoming more orderly and decorous in their relations otherwise.

A further object is to so construct and fabricate the different elements comprising the chest, that by re-arranging the parts, varied applications of the same may be made so as to present a change of appearance in the whole structure, thereby making of the device itself a sort of super-toy, in association with which other and smaller toys may be employed to provide wholesome amusement for the child or children.

With this object in view, I have equipped the chest with shelves and partitions by means of which the child may evolve a combination representing a miniature house, arranging the furnishings,—as toy furniture and bric-a-brac, according to his own fancy. With these removable parts, are also provided trays which are useful for holding small articles or for various other purposes which the child's imagination may suggest.

Characteristic structural features of the chest are the two-piece top, or cover, which may be utilized as a wide shelf, or by folding made to serve as a narrow, elevated one, and

the turn-down front member which supplies a convenient table upon which to deposit the toys preliminary to arranging them on the shelves.

While the novelty of the invention resides primarily in the structural combination of the parts to provide a receptacle for toys and a convenient means by which they may be displayed in various ways, it is further possessed of certain advantages which should not be lost sight of. For instance, in manipulating the parts to produce the different combinations, the child's mind is brought into action in planning and executing each procedure and this gives an opportunity for his mental development and the broadening of his powers of observation and concentration,—in which respect the invention is of considerable psychological value.

I have illustrated my invention by the use of the accompanying drawings in which like reference characters are employed to identify like parts throughout all the different views thereof.

In the drawings,—

Fig. 1 is a perspective view of the toy chest, closed;

Fig. 2 is a rear elevation thereof;

Fig. 3 is a fragmentary, transverse sectional elevation, showing the front side lowered;

Fig. 4 is a perspective view of the toy chest, opened;

Fig. 5 is a fragmentary perspective view, partly in section, showing a different disposition of the cover;

Fig. 6 is a detail connected with the fastening of the transverse partition;

Fig. 7 is a fragmentary side elevation of the chest, showing the cover disposed in a still different position;

Fig. 8 is a view, transversely of the chest, especially showing the detachable portion of the main partition, and,

Figs. 9 and 10 are perspective views of a tray and shelf, respectively.

Referring to the drawings, 1 represents the end members of the chest, 2 the back side and 3 the legs therefor; and on the ends of

the chest are the handles 4 with which to lift the chest when moved from place to place.

The front side 5 of the chest is secured, at its lower edge, to the bottom member 6 by the hinges 7, and to secure the front in closed and locked position I provide any convenient means,—as the sliding bolt 8, which, to lock the side, engages the hole 9 on the inside of the end member 1.

10 To properly support the front 5, when lowered, I provide swinging legs 10 which are housed beneath the chest when not in service, and pivoted thereto by the pins 11. When these swinging legs are extended, the 15 supporting pins 12 bear directly the weight of the front 5 when in lowered position, and hold it in a horizontal position, as seen in Fig. 3.

A partition 13 divides the chest into two 20 compartments, although it is obvious that three or more might be employed which would supply any number of compartments desired. This partition, as well as the end members 1, 1, have horizontal and vertical 25 grooves, 14 and 15, respectively. When operating in the grooves 14, the members 16 serve as shelves, but when re-arranged to fit in the grooves 15 they act as longitudinal partitions.

30 The trays 17 may be located on the shelves either lengthwise or crosswise of the chest; they may also be disposed bottom side up to provide a floor intermediate the shelves. They are principally used to hold the child's 35 small trinkets but by a little ingenuity on the part of the child they may be transformed into a cot or bed for a toy doll.

It is sometimes desirable to store articles 40 longer than can be contained in either one of the compartments. For this purpose I make a portion 13' of the partition 13, detachable, so that when this part is removed a space the inside length of the chest and a 45 width and height similar to the dimensions of the part 13' is provided. A latch button 18 on each side of the partition 13 holds the part 13' in place when it is incorporated as a part of the partition, but in this case the outer or front shelves 16 must be removed.

50 In the operation of removing the shelves 16, or when there were no shelves in position, the partition might be displaced from the back-board 2. To prevent this I provide construction shown in detail in Fig. 6.

55 A depression 19 is made in the top of the back board 2 and a thin metal bar or plate 20 bridges it. On the back side of the partition 13 is secured an off-set piece 21 which engages the plate 20 and holds the upper 60 end of the partition secure,—the groove 22 in the floor or bottom 6 of the chest providing means to hold the partition plumb.

The cover has been designed with a view 65 of making it one of the novel features in the chest.

It comprises two hinged sections, the outer one considerably wider than the inner one, the two parts, 23^a and 23^b, respectively, being just wide enough in aggregate width to cover the open top of the chest.

One edge of the section 23^b is hinged to the top of the back side member 2, swinging on the hinges 24, and preferably made to open to a horizontal position only, although the hinges may be so attached that it can 70 swing downward and lie flat against the side of the back member 2. The two sections are held in alignment when it is desired to make one wide shelf, by the swinging cleat 25 (see Fig. 4), but on releasing the cleat the section 80 23^a may be folded under and its outer edge located in the bracket 26, the hinges 27 permitting the two sections to be arranged as seen in Fig. 7.

Where space in the room is limited, this 85 latter arrangement permits of the chest being placed comparatively close to the wall,—the narrow section 23^b providing a mantel shelf upon which certain of the smaller toys may be assembled.

90 On the back side member 2 is a horizontally swinging bracket 28 which directly supports the full width cover when arranged as seen in Fig. 4.

95 On this bracket is pivotally secured a vertically swinging arm 29 which, when moved into upright position, supports the wide section 23^a when the cover parts are allocated as shown in Fig. 5. A brace 30 engages the angle plate 31 and holds the section 23^b in 100 vertical position. With this disposition of the parts an elevated and considerably wider shelf than that shown in Fig. 7 is provided.

105 For conveniently holding pens or pencils and preventing them rolling off the shelf I provide in the section 23^a the wells 32. A clasp 33 locks the cover on to the front side 5.

The chests are manufactured of a 110 commodeous size, approximately three feet long, giving ample space for storage and plenty of room for arranging or displaying the toys while the children are engaged in their amusements.

115 It is strongly built, of reasonably low cost and will, it is believed, be found a very useful and desirable acquisition in any home, more particularly as it may, in case of necessity, be utilized by the housewife to serve, after the interior parts are removed, as an ordinary chest in which to store clothing or like articles.

Having thus described my invention, what I claim and desire to secure by Letters Patent is:

125 1. A toy chest comprising a bottom member, two end members and one side member fixedly secured to said bottom member, a side member hinged at its lower edge to said bottom member, and adapted to close the open side of said chest, means, normally housed 130

- beneath said bottom member, adapted, when extended, to support said hinged side member in a horizontal position, co-acting means on said hinged side member and one of said end members whereby the former may be locked in a position closing the open side of said chest, a partition in said chest disposed transversely and vertically thereof, means to detachably secure said partition in said chest,
- 5 10 a plurality of shelves, means in said chest whereby said shelves may be disposed in two generally different positions in said chest,—horizontally and vertically, and a detachable section on said partition adapted to
- 15 provide, when removed, an unobstructed space of a length coextensive with the interior length of said chest and of a width and height similar to the corresponding dimensions of said detachable section.
- 20 2. A toy chest comprising a bottom member, two end members and one side member fixedly secured to said bottom member, a hinged side member adapted to close the open side of said chest, a two-piece cover, includ-
- 25 ing a wide and a narrow portion hingedly connected, said narrow portion also being hinged to the said fixed side member at its top, a swinging bracket located on said fixed side member and adapted, when in extended
- 30 position, to support both portions of said cover, an arm pivotally secured to said bracket and adapted, when moved to a vertical position, to support the wider portion only of said cover, and a brace pivotally secured to
- 35 one of the end members of said chest engageable with means on the narrower portion of said cover to hold the latter in a fixed vertical position.
3. A toy chest comprising a bottom mem-
- 40 ber, two end members and one side member fixedly secured to said bottom member, a side member hingedly connected at its lower edge to said bottom member and adapted, when vertically disposed, to close the open side of
- 45 said chest, brackets pivotally secured to the under side of said bottom member adapted to be extended to provide support for said hinged side member when horizontally disposed, a cover for said chest having two parts
- 50 of unequal width hinged together, hinges securing the narrower portion of the said two-part cover to the top of the said fixed side member, a bracket on the outer, lower side of the said fixed side member adapted to re-
- 55 ceive the outer edge of the wider portion of the said two part cover and transform the narrower portion thereof into a horizontal shelf, flush with the top of said chest, and a swinging bracket having an upwardly ex-
- 60 tending arm adapted to engage said wider portion and convert it into a horizontal shelf disposed at a spaced distance, vertically, above the top of said chest.
- 65 In testimony whereof I affix my signature.
PAUL R. STEVENS.
